DAMPER MECHANISM

Joseph P. Yochem, Columbus, Ohio

Application August 3, 1939, Serial No. 289,007

8 Claims. (Cl. 126—296)

This invention relates to control mechanism for heating plants and is particularly directed to a damper mechanism for use in a hot air furnace of the type used in domestic heating systems.

The primary object of this invention resides in the provision of a damper mechanism having a plurality of jointed sections which will permit the damper to be employed either in curved smoke conduits such as the secondary radiator of a hot air furnace or straight smoke pipes such as those used to convey the products of combustion from a furnace to a stack.

Another object of the invention resides in forming the damper with a plurality of baffle plates mounted for swinging movement from positions in which they will offer obstruction to the flow of smoke and gases through the conduit in which they are disposed to positions where they will offer a minimum of resistance to the passage of the products of combustion.

A still further object rests in constructing the baffle plates of the damper mechanism of such shape and size that when they are in fully closed positions, a small flow of smoke will take place over a tortuous path to slow up the movement of the heated gases whereby more heat will be extracted therefrom and consequent economy of operation of the furnace effected.

It is also an object to provide an operating device for the damper and to connect the damper plates to one another and the operating device in order that movement of the latter member will be transmitted to the former and individual attention of the operator to each baffle plate will not be required.

Another object rests in providing the above mentioned operating device with a graduated indicating dial by means of which the degree of opening and closure of the damper may be determined by the operator from the exterior of the furnace in which the damper mechanism is installed.

Other objects will become apparent from the following description of one form of the invention which has been disclosed in detail in the accompanying drawing.

In the drawing:

Fig. 1 is a perspective view of a secondary radiator or smoke ring of a furnace with parts broken away to show a damper mechanism constructed in accordance with the present invention installed therein;

Fig. 2 is a vertical longitudinal sectional view taken through the smoke ring and the damper

mechanism and showing the damper mechanism in a substantially closed position;

Fig. 3 is a similar view with the damper mechanism in an open position;

Fig. 4 is a vertical transverse sectional view taken on the plane indicated by the line IV—IV of Fig. 2;

Fig. 5 is a similar view taken through the smoke ring at the clean-out opening, the plane of this figure being indicated by the line V—V of Fig. 2;

Fig. 6 is a front elevational view of the operating lever of the damper mechanism.

Referring more particularly to the drawing, the damper mechanism, while being illustrated as installed in the smoke ring of a furnace, may be as readily incorporated in the flue leading to the outlet stack. This damper mechanism comprises a plurality of base bars 1 which are identical in construction, each having an ear 2 of reduced thickness at each end, one ear being disposed in a different elevation than the other ear. These ears are perforated for the reception of bolts 3 or other securing elements used to pivotally connect the base bars. At the central portion of the length of the base bars, they are each provided with an upstanding extension 4 which is of a height substantially equal to one-half of that of the conduit for which the damper mechanism is designed.

The stands have their upper ends perforated for the reception of a horizontally disposed transversely extending pin 5 provided at longitudinally spaced points with openings for the reception of cotter keys 6 provided for the purpose of limiting the longitudinal movement of the pin in the damper mechanism. Each of the pins supports for rocking movement a baffle plate 7, the rear surfaces of which in this instance are formed with transversely spaced lugs 8. When the plates are attached to the pins and the base bars, the stands 4 are positioned in the space between the lugs 8. The pins 5 extend through aligned perforations formed in the lugs and those provided in the stands 4. The cotter keys are disposed on the outer sides of the lugs to maintain the relation of the parts when the damper mechanism is in use. As illustrated in Fig. 4, the length of the pins 5 is greater than the transverse width of the baffle plates. This provision is made to maintain the plates in spaced relation from the side walls of the smoke ring 9 or other conduit in which the damper mechanism may be positioned.

Certain of the baffle plates have the upper ends

thereof formed with an upwardly directed ear 10 which is provided on its rear surface with a reduced eyelet 11. All of the plates have a similar eyelet 12 formed on the front surface, the latter eyelets being disposed in closer relationship to the fulcrum formed by the pins 5 than the eyelets formed on the ears 10. The stand 4 has been eliminated from one of the base bars and a larger stand 13 is secured to this base bar by a screw 14 which will permit the stand to be attached after the base bars have been installed in the smoke conduit.

The stand 13 is provided at its upper end with a horizontally disposed tubular extension 15 having a reduced threaded outer end 16. When the damper mechanism is employed in the smoke ring of a furnace, the extension 15 is directed outwardly through the clean-out branch 17 of the smoke ring, the outer end of this branch being closed by a plate 18 held in place by a nut 19 removably supported on the threads of the extension 15. A second plate 20 is carried by the extension 15 within the branch for the purpose of precluding lateral movement of the extension in the branch when the damper mechanism is in use. The extension 15 is slightly reduced at its outer end to receive a dial member 21 having indications on its outer face for the purpose of informing the operator of the damper mechanism of the position of the baffle plates within the smoke ring.

A shaft 22 is journaled for rotary movement in the extension 15 and has its outer end made square to key an operating handle 23 thereto, the handle being retained in position on the shaft by a nut 24 threadedly carried by the outer end of the shaft. The shaft is formed at its inner end with a double arm crank lever 25, the outer end of each arm having an opening 26 for the reception of a loop 27 formed at the end of a link 28. The opposite end of each link 28 also has a loop formed therewith which is engaged with the small eyelets 12 provided on the front faces of the baffle plates adjacent the lever 25. Similar links 29 extend between the eyelets 11 formed on the baffle plates and the eyelets 12 provided on the plates remotely positioned from the lever 25. In the present instance, the base bar having the stand 13 secured thereto is disposed between two pairs of base bars on which the baffle plates are supported. This arrangement permits one section of the damper mechanism to be placed at one side of the entrance to the smoke ring from the firepot of the furnace while the other set of baffle plates is disposed on the other side. Thus, when the products of combustion pass from the combustion chamber, they divide, a portion passing to one side through the smoke ring and the remaining portion passing to the other side and joining with the first portion at the outlet flue. This construction of smoke rings is the usual type in hot air furnaces and the damper mechanism has been designed specifically therefor in that the base plate having the large stand 13 formed therewith is positioned between two sets of bars having the smaller stands.

It will be apparent from Fig. 2 that the baffle plates are shorter in length than the height of the smoke ring to permit some gas flow when the damper is entirely closed. The plates are so arranged that the space for this gas flow at adjacent baffle plates will be disposed alternately at the top and bottom of the smoking ring which will cause the gases to move in a

tortuous path. This feature slows down the passage of gas through the smoke ring and provides for a greater transmission of heat to the walls of the ring. The baffle plates on the sections of the damper at opposite sides of the crank arm are disposed with their faces towards the crank arm to provide for adjustment in a similar manner upon rotation of the shaft.

By hinging the base bars to one another and connecting the crank arms and the baffle plates with links, the damper mechanism may be employed in either curved or straight sections of conduit and since the damper is made up of a plurality of small sections, the mechanism can be inserted into the smoke ring of a furnace through the clean-out opening and assembled after being disposed therein. To limit the degree of movement of the baffle plates, the indicator dial 21 is provided at either side of the pointer on the operating handle with a stop pin 30.

While but a single form of the invention has been illustrated, it is obvious that many minor changes may be made therein such as adding base bars and baffle plates or changing their shape without departing from the spirit and scope of the invention as set forth in the following claims.

I claim:

1. A damper mechanism for use in smoke conductors comprising a plurality of base bars pivotally joined to one another, an upwardly directed projection formed with each of said bars, a baffle plate pivotally supported at the upper end of each projection for movement about a horizontal axis, link means extending between said plates and coupling them for movement together, a pivoted crank arm having one end linked to one baffle plate, and means for moving said lever to impart swinging movement to said plates.

2. A damper mechanism for use in smoke conductors comprising a plurality of base bars pivotally joined at their ends, an upwardly directed stand formed with each bar, a baffle plate supported for pivotal movement around a horizontal axis at the upper end of certain of said stands, a horizontally extending shaft journaled in one of said stands, a crank arm secured for movement with said shaft, and link means connecting the outer end of said crank arm and said baffle plates.

3. A damper mechanism for use in smoke conductors comprising a plurality of base bars pivotally joined at their ends, an upwardly directed stand formed with each bar, a baffle plate supported for pivotal movement around a horizontal axis at the upper end of certain of said stands, a horizontally disposed bearing provided on one of said stands, a shaft positioned for rotation in said bearing, a crank arm secured to one end of said shaft, link means extending between said crank arm and said baffle plates, and an operating handle secured to the other end of said shaft.

4. A damper mechanism for use in smoke conductors comprising a plurality of base bars pivotally joined at their ends, an upwardly directed stand formed with each bar, a horizontally disposed pin extending through the upper ends of certain of said stands at right angles to the length of said base bars, a baffle plate supported for movement about the axis of each of said pins, the length of said pins being greater than the transverse dimension of said plates to hold them in spaced relation from the sides of the conduit in which the mechanism is disposed, a

5 crank arm supported for swinging movement about a horizontal axis on one of said stands, link means extending between said crank arm and said baffle plates, and means for imparting movement to said crank arms to adjust said baffle plates.

10 5. A damper mechanism comprising a plurality of duplicative base bars pivotally joined at their ends, an upwardly directed stand provided on each of said bars, said stands having transversely extending horizontally disposed openings at their upper ends, a pin positioned in certain of said openings, a baffle plate supported for pivotal movement on each pin, perforated eyelets formed on said plates in spaced relation to said pins, a shaft positioned in the transversely extending opening of one stand, an extension provided on the last-mentioned stand, said extension projecting to the exterior 15 of a smoke conductor in which the draft apparatus is positioned, an operating handle secured to the outer end of said shaft, a crank arm formed with the inner end of said shaft, and link means for transmitting movement from said 20 crank arm to said baffle plates.

25 6. In a damper mechanism, an odd number of duplicative base bars disposed in a row and pivotally connected at their ends, a stand extending upwardly from each bar, a horizontally disposed laterally directed bearing formed with the stand on the base bar disposed equidistantly from the ends of the row, a baffle plate supported for

pivotal movement on each of the other stands, a shaft rotatably received by said bearing, a crank arm extending from opposite sides of the inner end of said shaft, a link connecting the baffle plates at one end of the row of base bars 5 with one crank arm and a second link connecting the other baffle plates with the other crank arm, and an operating lever secured to the outer end of said shaft.

10 7. In a damper mechanism, a sectional longitudinally extending base, baffle plates pivotally supported by all but one of the sections of said base, adjusting means carried by the section without a baffle plate, and link means for transmitting movement from said adjusting means 15 to said baffle plates.

20 8. In a damper mechanism, a longitudinally extending base formed from a plurality of pivotally connected sections, baffle plates supported by certain of said sections for pivotal movement about axes disposed at right angles to the axes of the pivots connecting said base section, a pair of oppositely disposed crank arms supported for pivotal movement about an axis disposed at right angles to the axes of the pivots connecting said 25 base sections, and link means for transmitting movement from one of said crank arms to certain of said baffle plates, and additional link means connecting the other crank arm with the rest of said plates.
